TRIMBLE DE ROODE, OF NEW YORK, N. Y.

COMBINED TYPE-WRITING AND PRINTING MACHINE.

1,254,583.

Specification of Letters Patent. Patented Jan. 22, 1918.

Application filed May 16, 1914. Serial No. 838,913.

To all whom it may concern:

Be it known that I, TRIMBLE DE ROODE, a subject of the Queen of the Netherlands, residing in the borough of Manhattan, city and county and State of New York, have invented certain new and useful Improvements in Combined Type-Writing and Printing Machines; and I do hereby declare the following to be a full, clear, and exact description of the invention, such as will enable others skilled in the art to which it appertains to make and use the same.

This invention relates to combined typewriting and printing machines adapted for use in printing multiple copies of a circular letter and inserting the salutations in the several copies individually.

The object of the invention is to provide a combined typewriting and printing mechanism of this character which is simple in construction, which may be manufactured at low cost, which may be operated by unskilled persons and with which circular letters may be produced partly by a printing operation and partly by a typewriting operation with the typewritten and printed portions having the same appearance and the appearance of typewritten work. A further object of the invention is to so construct the mechanism as to permit of inserting not only the salutations, but also any other desired portions of the circular letters by means of the typewriting mechanism, the construction being arranged to facilitate operation of the typewriting mechanism to print the desired typewritten matter at the proper points on the sheet.

In accordance with the invention, a typewriting mechanism is provided with the usual roller platen movable transversely of the machine and, in addition thereto, a second platen adapted to be used in the printing operation, and a support for a type-form consisting of a multiplicity of individually set-up type is arranged in position to coact with this second platen. The platen coacting with the type-form is mounted upon the carriage of the typewriting machine so that it moves transversely thereof along with the roller platen under the control of the escapement mechanism. Also, this platen is mounted upon the typewriter carriage in such a position that the movement of the paper around the platen

roller, effected by the line-spacing mechanism of the machine, causes the paper to be forwarded over the surface of the second platen so that a succession of operations of the line-spacing mechanism will move the sheet of paper into the position required for printing thereon from the form of type. Preferably, the platen for coaction with the type-form is flat and is arranged in a vertical position immediately over the front of the roller platen of the typewriting machine. In addition to the two platens on the carriage of the typewriting mechanism, rollers are provided on the carriage for supporting the ends of an ink-ribbon which extends from one roller around the roller platen and then over the face of the flat platen to the other roller. This ink-ribbon supplies the ink for printing both from the key-levers of the typewriter and from the type-form so that the body of the letters printed on the machine and the salutation printed by the typewriting mechanism must necessarily be identical in color. Also, an adjustable stop is provided for limiting the pressure which the type-form may be caused to exert against the sheet and the coacting platen so as to further facilitate the production of letters which are identical in appearance both as to the body of the letter printed from the type-form and the salutation and other parts printed with the typewriter.

In order to aid the operator in positioning the sheet with reference to the platen roller when printing the salutation or any other portion of the letter which is to be printed with the typewriting mechanism, a plurality of adjustable stops is provided which may be positioned so as to arrest the movement of the sheet around the platen roller. When the edge of a sheet comes in contact with a stop positioned by the operator with reference to the desired arrangement of the printed matter upon the sheet, the operator knows that he may then operate the typewriting mechanism to print the salutation or other portion of the letter and that thereafter the matter printed with the type-form will be received upon the sheet in the desired relation to the matter previously typewritten thereon. In combination with these stops, means are provided for moving the edge of a sheet out of coaction with a stop after the stop has served its purpose.

The preferred embodiment of the invention is illustrated in the accompanying drawings, in which—

Figure 1 is a front view of the combined typewriting and printing mechanism;

Fig. 2 is a side elevation of the same, some of the parts being shown diagrammatically;

Fig. 3 is a detail view of a portion of the top of the machine;

10 Fig. 4 is a central section through the two platens, the type-form and the support for the type-form;

Fig. 5 is a perspective view of one of the stops;

15 Fig. 6 is a perspective view of one of the type; and

Fig. 7 is an elevation of an impression controlling device hereinafter described.

Referring to these drawings, a typewriting mechanism of the usual or any suitable construction is shown in Figs. 1 and 2, having a plurality of key-levers 7, operated by keys 8, in the usual manner. The typewriter has a transversely movable carriage 9, adapted to move under the control of an escapement mechanism in the usual manner, it being supported upon rails 10. In the particular type of typewriting mechanism chosen for illustration, the shifting of the 20 platen roller for printing upper and lower case letters is effected by moving the carriage 9 and all the parts mounted thereon in a vertical direction. For this purpose, one of the rails 10 is mounted upon supports 11 which may be moved upward by 25 means of a shift-key 12. The platen roller 13 is mounted for rotation in bearings formed upon the frame of the carriage 9 and its position is such that the type of 30 the key-levers 7 coat with the front face of the roller 13. Two reels are shown at 14 for use in supporting a narrow ink-ribbon which is adapted to extend between the arms of a 35 guide 15 (Fig. 1). This ink-ribbon mechanism, however, is that which is commonly employed with a typewriting mechanism of the construction chosen for illustration, and in adapting the machine for use in accordance with the present invention, this 40 ink-ribbon mechanism is not employed.

The carriage 9 of the machine has a second platen mounted thereon in addition to the roller platen 13 and these two platens together with the ink-ribbon mechanism employed therewith are adapted to move together transversely of the machine under the control of the escapement. The second platen is flat and is arranged in a vertical plane extending upwardly from the front 45 face of the roller platen 13. This flat platen is shown at 16; it consists of a sheet of hard rubber mounted upon a metallic base-plate 17. The plate 17 with the platen 16 affixed thereto is secured to the frame of the 50 carriage 9, as shown in Fig. 4, so that it

moves crosswise of the machine with the roller 13. The platen 16 forms one member of a printing couple, the other member of which consists of a form of type located directly opposite the platen 16 upon a supporting plate 18. This plate 18 has bearings 19 formed on the rear face thereof of which bearings receive eccentrics 20 mounted upon shafts 21, the plate 18 being adapted to slide upon the eccentrics 20 transversely of the machine. The two shafts 21 are mounted in bearings 22 secured to frame-members 23 rising from the base on which the typewriter mechanism is mounted. At one side of the machine, the shafts 21 extend through the bearings 22 and have cranks 24 secured thereto. The outer ends of these cranks 24 are connected by a link 25 and this link is pivotally connected to the upper end of a long lever 26. This lever 26 is connected to an operating lever of any suitable construction; in the present case, the operating lever is shown at a treadle 27 pivoted upon the floor and provided with a suitable foot-piece 28. An adjustable stop 30 is preferably provided adapted to coact with the lever 27 so as to limit the extent of its downward movement. Such an adjustable stop is shown at 29 in Fig. 2, it being mounted upon the floor under the support for the 95 machine.

The type of the type-form are preferably of the construction shown at 66 in Fig. 6. For the support of these type, a plate 30 is provided having a plurality of under-cut 100 grooves extending across the face of the plate in parallel relation as shown in Fig. 4. The type are individually assembled upon this plate 30 by moving them lengthwise into the grooves in the plate, the lines of type being held in proper position in their grooves by any of the well known means. The plate 30 may be provided with lugs or rails 31 adapted to be received in transverse grooves in the supporting plate 105 18 so that the plate 30 with the form of type thereon may be readily mounted in position and withdrawn when desired.

For the purpose of guiding the platen 16 in its transverse movement, a bar 32 is preferably provided extending between the frame-members 23 immediately in the rear of the plate 17. The front and rear faces of this bar are accurately finished and brackets 33 are secured to the plate 16 and extend in rear of the bar 32. These brackets are so spaced apart as to permit of a limited extent of vertical movement of the plate 17 and the platen thereon, such movement being effected by the shift-key 12 heretofore 120 referred to.

The transversely movable carriage also supports the ink-ribbon mechanism. This mechanism consists of a single ribbon of substantial width which extends around the 125

platens roller 13 and over the face of the flat platen 16. The ends of this ribbon are carried upon suitable rollers and one or both of these rollers is provided with mechanism for effecting the feeding of the ribbon. In Fig. 4, a roller is shown at 34 mounted upon the frame of the carriage 9 to the rear of the platen roller 13. The ribbon 35 extends from this roller 34 between a pair of guides, 10 and around the platen roller 13. These two guides, 36 and 37, are plates of thin sheet metal secured to the frame 9 of the carriage and having their forward ends curved so as to be concentric with the roller 13. Between 15 the two plates is a narrow space through which the ribbon 35 passes and between the plate 36 and the roller 13 is a narrow space through which the sheet of paper passes. The two plates 36 and 37 terminate on the 20 front side of the roller 13 immediately below the striking point of key-levers of the typewriter. The forward edge of the plate 36 is serrated and the fingers thus formed on the edge of the plate are bent inwardly as shown at 38 in Fig. 4. These fingers press 25 the sheet of paper against the roller 13 and thus insure feeding movement of the sheet as the platen roller 13 is turned and also hold the sheet against displacement when 30 the type-form is operated. The ribbon 35 passes vertically upward from the roller 13 between the platen 16 and the type-form and at its upper end is wound upon a roller 39. This roller is journaled in brackets extending 35 upwardly from the plate 17. On one end of the roller is a ratchet wheel 40 (Fig. 2) engaged by a pawl 41, pivoted on a pawl-carrying arm 42. This arm is loose on one 40 of the trunnions of the roller 39 and is moved in one direction by a spring 43 and in the opposite direction by a stop 44 secured upon the front face of the supporting plate 18. When the plate 18 is moved to carry 45 the type-form into coaction with the platen, its movement causes the arm 42 to be turned against the tension of spring 43, so that pawl 41 will turn the ratchet 40 and the roller 39 a distance equal to one tooth of the ratchet.

50 Each machine is provided with a plurality of stops which may be of the construction shown in Fig. 5. Each of these stops has a part 45 adapted to fit into the end of a groove in the plate 30, and a transversely disposed part 46 whose end extends into the path of movement of the sheet of paper to be printed upon. The several stops for a machine may be different as to the length of the portions 46 thereof. When a 55 stop such as that shown in Fig. 5 is seated in the end of a groove in the plate 30, as shown at 47 in Fig. 2, the movement of a sheet of paper effected by the line-spacing mechanism of the typewriter will carry the 60 edge of the sheet into engagement with the

stop. The stop will then arrest further movement of the sheet or the sheet will become bowed if the line-spacing mechanism is again actuated. In preparing the machine for use, the operator may place a stop 70 in such position that it will be engaged by a sheet when the sheet is in position for typewriting the salutation. Or, several stops may be arranged in position for arresting the sheet at several positions corresponding 75 to the positions where typewritten matter is to be inserted. In order to permit of moving a sheet beyond the position in which it coacts with the stop, a strip 48 is provided at one edge of the plate 18. This strip is carried 80 by arms 49 which are pivotally mounted upon the top and bottom of the plate 18. The strip has a plurality of slots cut in its edge of a width slightly greater than that of the portions 46 of the stops and the fingers 85 formed by the provision of these slots are bent inwardly as shown in Fig. 3. Secured to or formed integral with the lower arm 49 is a lever 50. By moving this lever, the several fingers of the strip 48 may be moved 90 forward so as to engage a sheet which has been arrested by a stop and move the edge of the sheet with the fingers until it is carried beyond the end of the stop. The slots in the strip 48 permit the strip to pass over 95 any stops which have been positioned in the type-channels. The sheet may then be moved upward to a further extent by operation of the line-spacing mechanism.

It may occur sometimes that when a sheet 100 has reached such position that its edge is in contact with a stop and the operator is writing with the typewriting mechanism, it will be necessary to shift the carriage vertically for printing an upper case letter. In 105 order that shifting of the carriage at such time may not cause bowing of the sheet due to its coaction with the stop, I provide means for effecting the automatic actuation of the comb-plate 48 by the carriage-shift- 110 ing mechanism. For this purpose, the frame of the carriage has a lever 51 (Fig. 2) secured thereto having a cam surface 52 which normally lies under and in front of the lever 50. When the carriage is raised 115 vertically by operation of the shift-key, this cam surface acts on the lever 50 so as to cause it to move in the direction for actuating the comb-plate 48 in the manner above described.

The ends of the shaft of roller 13 are received in depressions in the frame of carriage 9 as shown in Fig. 2 and are held therein by strips 58 which may be moved out of the way by handles 59 thereon. When 125 thus moved, the platen roller, the flat platen 16, the ribbon mechanism, and the parts associated therewith may be raised out of coaction with the typewriting machine.

The platen roller 13 is provided with the 130

usual turning knob 54 and the lever 53 for effecting line-spacing and it will be noted that the knob and the handle of the lever 53 are conveniently positioned with respect to the lever 50 so that when it is necessary to do so, the operator may move both lever 50 and knob 54 simultaneously with one hand, such simultaneous operation being desirable when the sheet of paper is in contact with a stop and it is desired to effect a line-spacing movement of the sheet. An impression controlling device for the type-written matter is shown in Figs. 1 and 7. This consists of a spring metal piece 55 secured to the ribbon guiding device 15 and arranged to be struck by each of the key-levers 7 just as the latter is brought to the position for striking the sheet. This piece is shown in Figs. 1 and 7 as mounted on the guide 15 for the ink-ribbon of the typewriting machine. This guide is provided with a screw 56. To position the piece 55, this screw is loosened and the fingers 57 of the piece 55 are passed over it. These fingers are bent inwardly as shown in Fig. 7 so that they bear against the guide 15 and the screw 56 may be tightened up such an amount as will hold the piece 55 in the desired position. The upper end of piece 55 presents two diverging arms 30 and a curved edge between them. The upper end of each key-lever will strike this upper end of the piece 55 at a point on the key-lever near the type thereon. By adjusting the position of piece 55 with screw 56, the strength of the blows of the key-levers upon the sheet may be decreased to any desired extent. This impression controlling device aids materially in the production of printed and typewritten letters which are the same in appearance over all parts thereof, particularly, when the typewriting is done by an operator who strikes the keys with considerable force and who, without the use of the impression controlling piece 45 would print the typewritten matter with a heavier impression than it would be desirable to obtain when printing from the type-form.

The operation of the mechanism thus constructed will now be described. The body of a letter is set up by suitably arranging type in the channels in the plate 30. If desired, the type-form may be arranged to print the entire letter except for the salutation, or spaces may be left at various points in which any desired words may be inserted by typewriting. This having been done, the plate 30 is positioned upon the supporting plate 18 by arranging it at one side of the plate 18 and then moving it laterally so that the lugs or rails 31 enter the grooves provided in the plate 18. The edge of a sheet of paper is then inserted between the rear face of the platen roller 13 and the guide-piece 36, and the roller 13 is then ro-

tated to carry the sheet around the roller until its edge projects beyond the edge of the fingers 38. A stop such as that shown in Fig. 5 is placed in the end of a channel of the plate 30 in such position that it will be engaged by the edge of the sheet when the sheet is in the position for receiving the salutation or other matter to be written with the typewriting mechanism. The roller 13 is then turned until the edge of the sheet 75 engages this stop whereupon the typewriting mechanism is operated in the usual manner to print the salutation. This having been done, the operator manipulates the lever 50 so as to cause the edge of the sheet 80 to be disengaged from the stop and at the same time turns the platen roller 13. If no other matter is to be typewritten, the roller 13 is turned so as to carry the sheet upwardly between the ribbon 35 and the platen 85 16 until the proper position of the sheet with respect to the type-form is shown by the engagement of the edge of the sheet with another stop positioned in a higher channel of the plate 30. The sheet will still be held 90 against accidental displacement by the fingers 38, which, throughout the operation above described are in engagement with the sheet. At this time or before moving the sheet upwardly, the carriage is moved to a 95 predetermined position with reference to the coacting scale on the frame of the typewriter so that the sheet will be in proper position for printing with reference to the type-form. The operator then presses the 100 operating lever 27, thus rocking the shafts 21 in their bearings and when the shafts are so rocked, the eccentrics thereon cause the plate 18 and the type-form supported thereby to move toward the platen 16 so that the 105 printing faces of the type in the type-form engage the sheet through the inking ribbon with the desired degree of pressure. On release of the lever 27, a spring 65 returns it to its normal position thus retracting the 110 type-form and the operator may then turn roller 13 until the upper edge of the sheet is carried above the platen 16 far enough to permit of grasping it and withdrawing it from between the type-form and the platen. 115 The support for the type-form and the typewriting mechanism are so positioned relatively that a word printed on a sheet with the typewriting mechanism will align accurately with words printed from the type-form intended to be read in the same line with the typewritten word or words. This makes it possible to have one or more words of a line in the body of a letter typewritten while the other words in the same line are 120 printed without the difference in the method employed appearing on inspection of the letter.

It will be seen that in this way multiple copies of a letter may be printed from a 130

type-form and on each one of the copies an individual salutation may be written with the typewriting mechanism. These two printing operations are effected with the 5 same ink-ribbon so that objectionable differences in the appearance of the completed matter such as are almost invariably present when part of the printing is done with one ribbon and the remainder with another 10 are avoided. It will be noted also that there is no restriction as to the location of the typewritten matter with respect to the matter printed from the type-form; not only may the salutation be written in with the 15 typewriter, but also any other part or parts of the complete letter may be typewritten. This requires merely that suitable spaces be provided when setting up the form of type and the positioning of stops to aid the operator 20 in typewriting at the points corresponding to these spaces.

The provision of an adjustable stop for arresting the movement of the mechanism for printing from the type-form is important in that it limits the degree of pressure 25 of the type-form upon the sheet; in this way, it is possible to guard against having some of the letters printed from the type-form much heavier than others as a result of 30 which differences in the appearance of the body and salutation of the letters would appear, at least upon some of the copies.

What I claim as new and desire to secure by Letters Patent of the United States is:

35 1. The combination with a typewriting machine having a movable carriage, of a platen mounted on the carriage in position to coact with the type of the typewriting machine, a second platen also mounted on 40 the carriage and movable therewith, means for moving the first platen and thereby moving a sheet from the first platen over the surface of the second platen, means independent of the first platen for supporting 45 a form of type in position to coact with said second platen and means for moving the second platen and the form of type relatively to effect printing from the form of type.

2. The combination with a typewriting 50 machine having a movable carriage, of a platen mounted on the carriage in position to coact with the type of the typewriting machine, a second platen having a flat face also mounted on the carriage and movable 55 therewith, means for moving the first platen and thereby moving a sheet from the first platen over the surface of the second platen, means independent of the first platen for supporting a plurality of type in a plane in 60 position to coact with said second platen and means for moving the said type and the second platen relatively to effect printing from the type.

3. The combination with a typewriting 65 machine having a movable carriage, of a

platen mounted on the carriage in position to coact with the type of said machine, a second platen also mounted on the carriage and movable therewith, means for supporting an ink-ribbon mounted on the carriage 70 and movable therewith, an ink-ribbon held by said means in coaction with both of said platens, both of the platens being located on the same side of the ink-ribbon, and means for supporting a form of type in position to coact with said second platen. 75

4. The combination with a typewriting machine having a movable carriage, of a platen mounted on the carriage in position to coact with the type of said machine, a 80 flat platen mounted on the carriage with one end adjacent to said first mentioned platen and movable with the carriage, means for supporting an ink-ribbon mounted on the carriage and movable therewith, an ink-ribbon held by said means in coaction with both of said platens, both of the platens being located on the same side of the ink-ribbon, and means for supporting a form of type with the type thereof in a plane in position to coact with the flat platen. 85

5. The combination with a typewriting machine having a movable carriage, of a platen mounted on the carriage in position to coact with the type of the typewriting machine, a second platen mounted on the carriage adjacent to said first-mentioned platen, line-spacing mechanism for actuating the first-named platen and moving a sheet from the same and over the surface of said second 95 platen, means independent of the first platen for supporting a form of type in position to coact with said second platen and means for moving the form of type and second platen relatively to effect printing from the form 100 of type.

6. The combination with a typewriting machine having a movable carriage, of a platen mounted on the carriage in position to coact with the type of the typewriting machine, a second platen mounted on the carriage with one end adjacent to said first mentioned platen, line-spacing mechanism for actuating the first-named platen and moving a sheet from the same over the surface of said second platen, means for supporting an ink-ribbon mounted on the carriage, an ink-ribbon held by said means in coaction with said platens, and means for supporting a form of type in position to coact with said second platen. 110 115

7. The combination with a typewriting machine having a movable carriage, of a platen mounted on the carriage in position to coact with the type of the typewriting 125 machine, a flat platen mounted on the carriage in a substantially vertical position with its lower edge adjacent to said first mentioned platen, means on the carriage for supporting an ink-ribbon, an ink-ribbon 130

held by said means in coaction with both of said platens, both of the platens being located on the same side of the ink-ribbon, and means for supporting a form of type in position to coact with said flat platen.

8. The combination with a typewriting machine having a movable carriage, of a platen mounted on the carriage in position to coact with the type of the typewriting machine, a second platen mounted adjacent to said first-mentioned platen, line-spacing mechanism on the typewriting machine for actuating the first-named platen and for moving a sheet of paper from the first-named platen to and over the surface of said second platen, means independent of the first platen for supporting a form of type in position for coaction with the sheet overlying said second platen and means for moving the form of type and the second platen relatively to effect printing from the form of type.

9. The combination with a typewriting machine having a movable carriage, of a platen mounted on the carriage, a second platen mounted adjacent to said platen so that a sheet may move from the first platen over the surface of said second platen, means for supporting a form of type in position to coact with said second platen, an operating device for causing relative movement of the form of type and said second platen to effect the printing, and an adjustable stop for limiting the movement of said operating device.

10. The combination with a typewriting machine having a movable carriage, of a platen mounted on the carriage, a second platen mounted adjacent to said first-mentioned platen so that a sheet may be moved from the same over said second platen, an adjustable stop adapted to be mounted in position to be engaged by the edge of a sheet forwarded over the surface of said second platen, and means for supporting a form of type in position to coact with said second platen.

11. The combination with a typewriting machine having a movable carriage, of a roller platen mounted on the carriage, a flat platen mounted on the carriage with one edge adjacent to said roller platen, line-spacing mechanism for turning the roller platen and moving a sheet from the roller platen over the surface of the flat platen, an adjustable stop adapted to be engaged by the edge of a sheet when the sheet is being moved over the surface of the flat platen, and means for supporting a form of type in position to coact with said flat platen.

12. The combination with a typewriting machine having a movable carriage, of a platen mounted on the carriage, a second platen mounted adjacent to said first-mentioned platen so that a sheet may be moved

from the same over the surface of the second platen, a stop adapted to be mounted in position to be engaged by the edge of a sheet when the latter is being moved over the surface of said second platen, means for moving a sheet out of coaction with the stop, and means for supporting a type-form in position for coaction with said second platen.

13. The combination with a typewriting machine having a movable carriage, of a platen mounted on the carriage, a second platen mounted adjacent to said first-mentioned platen so that a sheet may be moved from the first platen over the surface of the second, a stop adapted to be engaged by a sheet so moved, case-shifting mechanism for moving said first platen bodily, and means actuated by operation of said mechanism for moving a sheet out of coaction with said stop.

14. The combination with a typewriting machine having a movable carriage, of a platen mounted on the carriage in position to coact with the type of the typewriting machine, a flat platen mounted on the carriage adjacent to said platen, line-spacing mechanism for actuating said first-named platen to move a sheet from the same to and over the surface of the flat platen, and means for supporting a form of type with the type thereof in a plane in position to coact with said flat platen.

15. The combination with a typewriting machine having a movable carriage, of a platen mounted on the carriage in position to coact with the type of the typewriting machine, a flat platen mounted on the carriage in a substantially upright position with its lower edge adjacent to said platen, means independent of the first platen for supporting a form of type in position to coact with said flat platen, and means for moving the form of type and second platen relatively to effect printing.

16. The combination with a typewriting machine having a movable carriage, of a platen mounted on the carriage in position to coact with the type of the typewriting machine, a second platen mounted in a substantially upright position with its lower edge adjacent to said platen, an ink-ribbon extending over both of said platens with both platens lying on the same side of the ribbon, means for supporting a form of type, and means for moving the form of type and said second platen relatively to effect printing from the type-form.

17. The combination with a typewriting machine having a movable carriage, of a platen mounted on the carriage in position to coact with the type of the typewriting machine, a second platen mounted on the carriage with one of its edges adjacent to said first-mentioned platen, means on the car-

riage for supporting an ink-ribbon, an ink-ribbon supported by said means and extending over the surfaces of both of said platens, means independent of the first platen for supporting a form of type in coöperative relation to the second platen and means for moving the second platen and the form of type relatively to effect printing.

18. The combination with a typewriting machine having a movable carriage, of a platen mounted on the carriage, a second platen mounted adjacent to said platen so that a sheet may move from the first platen over the surface of the second platen, an ink-ribbon extending over both of said platens with both platens lying on the same side of the ribbon, means for supporting a form of type in position to coact with the second platen and an operating device for causing relative movement of the form of type, and said second platen to effect the printing.

19. The combination with a typewriting machine having a movable carriage, of a platen mounted on the carriage in position to coact with the type of the typewriting machine, a second platen mounted adjacent to said first mentioned platen, line-spacing mechanism for feeding a sheet about the first platen and over the surface of the second platen, means for holding the sheet in position after it has been moved over the surface of the second platen, means independent of the first platen for supporting a form of type in position to coact with said second platen, and the sheet so held, and an operating device for causing relative movement of the form of type and said second platen.

20. The combination with a typewriting machine having a movable carriage, of a platen mounted on the carriage in position to coact with the type of the typewriting machine, a second platen mounted adjacent to said first mentioned platen, line-spacing mechanism for feeding a sheet about the first platen and over the surface of the second platen, means for pressing a sheet into engagement with the first-named platen and thereby holding the sheet immovable after it has been moved over the surface of the second platen and while printing upon the sheet, and means independent of the first platen for supporting a form of type in position to coact with said second platen.

21. The combination with a typewriting machine having a movable carriage, of a platen mounted on the carriage in position to coact with the type of the typewriting machine, a second platen mounted adjacent to said first mentioned platen, line-spacing mechanism for feeding a sheet about the first platen and over the surface of the second, means for sustaining a sheet in one position in coaction with said first platen and in another position while overlying said second platen, means independent of the first platen

for supporting a type-form in position to coact with said second platen, and means for moving the type-form and the second platen relatively while the sheet is sustained in position overlying the second platen. 70

22. The combination with a typewriting machine having a movable carriage, of a platen mounted on the carriage in position to coact with the type of the typewriting machine, a second platen mounted on the carriage adjacent to said first-mentioned platen, line-spacing mechanism for feeding a sheet about the first platen and over the surface of the second one, case-shifting mechanism for simultaneously shifting the two platens and means for supporting a form of type in position to coact with said second platen. 75 80

23. The combination with a typewriting machine having a movable carriage, of a platen mounted on the carriage in position to coact with the type of the typewriting machine, a second platen mounted on the carriage adjacent to said first mentioned platen so that line-spacing movement of a sheet about the first platen carries the sheet over the surface of said second platen, means independent of the first platen for supporting a type-form in position to coact with said second platen and an impression controlling device adapted to be engaged by the type of the typewriting mechanism. 90 95

24. The combination with a typewriting machine having a movable carriage, of a platen mounted on the carriage in position to coact with the type of the typewriting machine, a second platen mounted adjacent to said first mentioned platen so that line-spacing movement of a sheet about the first platen carries the sheet over the surface of said second platen, line-spacing mechanism for actuating the first platen and the sheet coacting therewith, and means independent of the first platen for supporting a form of type in position to coact with said second platen and so disposed with relation to the first platen that printing effected by the typewriting mechanism will align with printing effected by the type-form. 100 105 110

25. The combination with a typewriting machine having a movable carriage, of a platen mounted on the carriage in position to coact with the type of the typewriting machine, a flat platen mounted in a substantially vertical plane with its lower edge adjacent to said first-mentioned platen whereby line-spacing movement of a sheet about the first platen carries the sheet over the surface of the second platen, means for supporting a form of type with the type thereof in a plane in position to coact with said flat platen and means for moving the flat platen and the type-form relatively to effect printing from the type. 115 120 125

26. The combination with a typewriting

- machine having a movable carriage, of a platen mounted on the carriage in position to coact with the type of the typewriting machine, a second platen mounted adjacent to the first mentioned platen so that a sheet may move from the latter over the surface of the second platen, an ink-ribbon extending in coöperative relation to both of the platens, means independent of the first mentioned platen for supporting a type-form in position to coact with said second platen, and an impression controlling device adapted to be engaged by the type of the typewriting mechanism.
27. The combination with a typewriting machine having a movable carriage, of a platen mounted on the carriage in position to coact with the type of the typewriting machine, a second platen mounted adjacent to the first mentioned platen, means for moving the first platen and thereby moving a sheet from the first platen over the surface of the second platen, means independent of the first mentioned platen for supporting a type-form in position to coact with said second platen, and an impression controlling device adapted to be engaged by the type of the typewriting mechanism.
28. The combination with a typewriting machine having a movable carriage, of a platen mounted on the carriage in position to coact with the type of the typewriting machine, a second platen mounted on the carriage with one of its edges adjacent to the first mentioned platen, means on the carriage for supporting an ink-ribbon in coöperative relation to both platens with both of the platens lying on the same side of the ribbon, and means for supporting a type-

form in coöperative relation to the second platen.

29. The combination with a typewriting machine having a movable carriage, of a platen mounted on the carriage, a second platen mounted adjacent to the first mentioned platen so that a sheet may move from the latter over the surface of the second platen, means for pressing a sheet into engagement with the first mentioned platen and holding the sheet after it has been moved over the surface of the second platen, an ink-ribbon supported in coöperative relation to both platens with both of the platens located on the same side of the ribbon, and means for supporting a form of type in position to coact with the second platen.

30. The combination with a typewriting machine having a movable carriage, of a platen mounted on the carriage, a second platen mounted adjacent to the first mentioned platen so that a sheet may move from the first platen over the surface of the second platen, means for sustaining a sheet in one position in coaction with the first platen and in another position while overlying the second platen, an ink-ribbon supported in coöperative relation to both platens with both of the platens located on the same side of the ribbon, and means for supporting a type-form in position to coact with said second platen.

In testimony whereof I affix my signature, in presence of two witnesses.

TRIMBLE DE ROODE.
